Primary Examiner — David G Muller*Assistant Examiner* — Christina Gabrielle Cosden(57) **CLAIM**

The ornamental design for offset pliers, as shown and described.

DESCRIPTION

FIG. 1 is a top-front-left perspective view of offset pliers showing my new design;

FIG. 2 is a bottom-rear-right perspective view thereof;

FIG. 3 is a top plan view thereof;

FIG. 4 is a bottom plan view thereof;

FIG. 5 is a left-side elevational view thereof;

FIG. 6 is a right-side elevational view thereof;

FIG. 7 is an enlarged front elevational view thereof;

FIG. 8 is an enlarged rear elevational view thereof;

FIG. 9 is a top-front-left perspective view thereof, wherein the present invention is shown in an open configuration; and, FIG. 10 bottom-rear-right perspective view thereof.

The broken line showing a set of handles in FIG. 1 through 10; and the gripping surfaces in FIGS. 9 and 10 is included for the purpose of illustrating environmental structure and forms no part of the claimed design.
